UNITED STATES PATENT OFFICE.

WALTER LOUIS CLEMENS, OF MILWAUKEE, WISCONSIN.

DESIGN FOR A WASHSTICK-HOOK.

49,989.

Specification for Design.

Patented Dec. 5, 1916.

Application filed August 1, 1916. Serial No. 112,619. Term of patent 14 years.

To all whom it may concern:

Be it known that I, WALTER LOUIS CLEMENS, a citizen of the United States, residing at Milwaukee, in the county of Milwaukee, State of Wisconsin, have invented a new, original, and ornamental Design for Washstick-Hooks, of which the following is a specification, reference being had to the accompanying drawing, forming part thereof.

Figure 1 is a front elevation of the wash

stick hook; Fig. 2 is a side view; Fig. 3 is a rear elevation.

I claim:

The ornamental design for a wash stick hook as shown.

WALTER LOUIS CLEMENS.

Witnesses:

HENRY HELLER,
IRMA LIEBSCHER.
